UNITED STATES PATENT OFFICE

ALFRED BREDEMBERG, OF CHAMPLAIN, NEW YORK, ASSIGNOR OF ONE-HALF TO THE SHERIDAN IRON WORKS, A CORPORATION OF NEW YORK, AND ONE-HALF TO T. W. & C. B. SHERIDAN COMPANY, A CORPORATION OF NEW YORK

BOOK BINDING OR COVERING MACHINE

Application filed November 14, 1927. Serial No. 233,105.

This invention relates to bookbinding or covering machines, such as are used for performing the various operations in the manufacture of books, pamphlets, pads and the like; and relates more particularly to the type of machine exemplified by my prior Patent 1,248,252, granted November 27, 1917, wherein in a succession of books is carried along progressively by means of a conveyor or carrying mechanism moving continuously through the machine while each of the successive books is operated upon by the several mechanisms which perform the desired operations thereupon, such for example as trimming, gluing, the application of fabric strips or supers, or of paper or other covers, followed by the shaping or breaking of the covers.

The general object of the present invention is to improve the coordination of the several elements of the machine, and especially to afford exact synchronism of action of the successive mechanisms operating upon the book with the advancing travel conveyor that carries the books continuously through the machine. A particular object is to avoid a certain drawback in machines of the class referred to which may be explained as follows. When a series or train of book clamps or other form of book conveyor is driven continuously through a sprocket mechanism, analogous for example to that shown in my said prior patent, a slight periodic or regular variation or weaving movement of travel occurs. This is due to the fact that the actuation of the conveyor by the driving sprocket, as seen in the prior patent, involves a slight but unavoidable variation in advancing movement due to the slight change of radius of the sprocket wheel at and between the bearing points of the sprocket wheel; the conveyor traveling slightly faster when the line of drive is tangent to a bearing point of this sprocket wheel than when half way between two such bearing points. Thus, notwithstanding a steady uniform source of drive of the sprocket wheel the books will depart regularly from a uniform or average speed. If now any of the operating mechanisms, such as the cover applying mechanism, is actuated in time with the continuous travel

of the conveyor, but in a steady uniform manner, there will be substantial but not exact synchronism. The mechanism will operate at a speed equivalent to the average speed of book travel, while the latter will vary slightly as described. There will result relative longitudinal movements, first forwardly and then backwardly, between the operating mechanism and the book, which although slight in extent, are undesirable and likely to produce slight lack of coordination or register in the binding or covering actions.

The present invention overcomes the described drawback without sacrificing the advantages of the sprocket driven type of book conveyor. Exact synchronism of travel is attained with the present invention by giving to the cover applier or other operating mechanism the same periodic variation of action or motion as that of the train of books, namely by connections from the source of drive operating independently of the book conveyor but delivering the same variable motion or action, this being herein illustrated as working through a sprocket or equivalent delivering the same periodic variation as that of the sprocket which drives the book conveyor. This improvement is herein illustratively shown as embodied in a combination wherein are two similar sprocket wheels, in time with each other, and both driven from the same power source or shaft, and both having the same number of points or bearings, one of them driving the book conveyor or clamp train and the other driving the cover applying or other operating mechanism. Specifically there is preferably an endless train of book clamps advanced continuously by the first sprocket, and an endless or rotary operating device or train of operating devices continuously advanced in exact synchronism with the variable book travel.

Other and further objects and advantages of the invention will be pointed out in the hereinafter following description of an illustrative embodiment thereof or will be understood to those skilled in the art to which the invention pertains. To the attainment of

such objects and advantages the present invention consists in the novel bookbinding or covering machine and the novel features of combination, arrangement, operation, mechanism and detail herein illustrated or described.

In the accompanying drawings Fig. 1 is a general top plan view of a bookbinding machine in which the present invention is embodied.

Fig. 2 is a similar plan view but on a larger scale of a portion of the machine, with certain parts broken away for purposes of better illustration.

Fig. 3 is a side elevation of the elements seen in Fig. 2.

Fig. 4 is a transverse section taken on the line 4—4 of Fig. 2.

Fig. 5 is a transverse section taken on the line 5—5 of Fig. 3.

The machine hereof is shown as comprising a general frame 10 on which are fixedly mounted the guides or upper and lower rails 11 around which the conveyor travels. The source of power is indicated as a longitudinal drive shaft 13 which may in turn be driven with reduction of speed from another shaft driven by motor or otherwise. At the right hand end of the drive shaft 13 is shown a bevel pinion 14 engaging a large bevel gear 15 secured on an upright shaft 16 which also carries the main sprocket wheel 17 turning in a horizontal plane and having a convenient number, as six, bearing points or recesses 18 for engagement by the conveyor or clamp train.

The conveyor is shown as composed of an endless series of connected clamps 20 articulated by a series of upright pins 21 which connect or hinge together the individual clamps, and each pin having upper and lower rolls 22 running in the clamp guide rails 11 throughout the greater part of their travel, but engaging the recesses 18 of the main sprocket wheel when passing around the right hand end of the machine. Each clamp may consist of an inner clamping plate 23 and an outer plate 24 enclosing between them the book B which is held upright with its back downward. As is usual in the type of clamp train machine of said patent the outer plates 24 may be provided with guide rods 25 which extend inwardly and are surrounded by coil springs 26 which operate to close each clamp, there being also a stud 27 arranged to be thrust outwardly for opening each clamp to receive or discharge each book and released to clamp each book.

The above described clamp train conveyor and the sprocket means for driving it are substantially well known and illustrated in my said prior patent. The drive shaft turns with uniform motion and so does the main sprocket from which the clamp train takes its motion. This mode of driving a conveyor

is highly efficient and desirable but incurs the periodic variation of driven speed of travel of the clamps and books as already described. There will hereinbelow be described an illustrative mechanism for operating upon the successive books, namely for applying covers to the back edges of the books and for pressing the same firmly into place. According to this invention, instead of driving the operating mechanism with uniform action from the drive shaft it is actuated with the same periodic variation as the clamp and book travel, namely by means of a second or auxiliary driving sprocket wheel in an arrangement synchronizing with the first sprocket wheel and conveyor travel.

The illustrative means for applying and pressing covers C to the backs of the books B is shown as comprising a series or endless train of platens or press bars 29, interconnected and arranged to come into operative position, travel along with the successive books while acting on them, and thence returning in an endless path for repetition of action. Each pressure platen or bar 29 is shown as having slanted extensions 30 at its ends, one of these being yoked and thus permitting each pair of bars to be connected by pins 31, affording an articulated train somewhat similar to the clamp train but traveling in an orbit or path which is vertical or at right angles to the horizontal orbit of the clamp train, although this particular relation of orbits is not essential. Each connecting pin 31 between the two pressure bars is provided with rollers 32 and these rollers are shown as guided in their path, namely along a top guide rail 33, a curved left guide rail 34 and a bottom rail 35, supported on the machine frame or braced by means of brackets 36. At its right hand end the train of pressers 29 passes off the top guide rail 33 and thence around a large sprocket wheel 38 from which in turn the pressers pass beneath the bottom rail 35. The auxiliary sprocket 38 is preferably of the same size as the main sprocket wheel 17 and both of the sprocket wheels have the same number of bearing points or recesses, for example six in number. Also the two sprocket wheels are arranged in synchronism, that is to say each bearing recess receives a roller at the same point of time, as will be clear by comparing the positions of the two sprockets in Figs. 1 and 3. In each of these figures the sprocket wheel is in such position as to deliver drive at the minimum speed, slightly less than the average speed of the clamp train or presser train; and in each case the speed will slightly accelerate until the maximum has been attained when the bearing recesses and rollers arrive at the respective points of tangency. By this arrangement the periodic variation of motion in the clamp train is followed with close exactitude in the motion

of the presser bar train. Therefore during the operation whereby each presser bar applies each cover to each book and thereafter presses it forcibly in place, there will be not the slightest relative motion between the book and the bar, thereby any inaccuracy or injury to the book or cover is avoided.

The auxiliary sprocket wheel 38 may be driven in a uniform manner in time with the main sprocket wheel as follows. The auxiliary sprocket is shown mounted on a transverse shaft 40 which extends inwardly and carries a large bevel gear 41 which in turn engages a bevel pinion 42 on the drive shaft 15 13, the gear ratios being such as to deliver identical rotation to the two sprocket wheels. Thereby, as already stated, the travel of the book clamps and books and the action or movement of the devices acting upon the 20 books will be in precise harmony and synchronism.

In order to supply or feed covers to be applied and pressed to successive books by the platens or bars 29 any suitable sheet feeding mechanism may be employed, delivering by means of tapes or sprocket chains to the applying position. Each cover C may move into applying position supported on a system of fixed strips or plates 45 indicated 25 in Fig. 5, as is well understood. The actual feeding or advancing of the successive covers may be by a pair of opposite feed chains 46, carrying upstanding pins 47 spaced apart longitudinally to correspond with the spacing 30 of the clamp train. From the left side of Fig. 3 each cover feeding chain 46 is shown as passing over a supporting sprocket wheel 48 and thence forwardly through the applying position to a sprocket wheel 49 on shaft 50 around which the chain passes for its return 35 travel.

It will be understood that at the far side of the machine a book has been fed into each clamp of the clamp train, the clamp being thereupon closed upon the book, and at a later point the back of the book being supplied with adhesive. Each cover therefore when applied to the back of the corresponding book adheres and is carried forward with the book, 40 while the upstanding feed pins 47 on the sprocket chains 46 disengage the covers.

The covers are not herein applied to the books by the feed chains, which merely bring the covers into applying position. Each cover is applied to its book by the corresponding platen or presser bar 29. It will be clearly seen from Fig. 3 that each of these bars comes up into applying position with a swinging motion around its foremost end or pivot pin. As the rearmost pivot pin passes from the curved guide rail 34 on to the straight horizontal top guide rail 33, the bar comes into pressing contact with the book back and thereby forces the cover into adhering contact with the book, after which each 45

presser bar continues in uninterrupted pressing contact through an extended length of travel, illustrated as substantially three book clamp lengths.

As an additional feature hereof provision is made for causing advancing feed of the covers at a speed and in a manner harmonizing with that of the platens or presser bars, and therefore in synchronism also with the travel of the books, thereby insuring that the 50 55 covers and books will be in exact register at the moment of application.

This result is preferably obtained by mechanical driving engagement between the train of bars 29 and the cover feeding chains 50 55 46. For this purpose there is shown an intermediate or short sprocket chain 52 located horizontally slightly outwards of the path of the presser bars. This local or connecting chain is shown engaged around a sprocket 85 wheel 53 on the same shaft 50 with the sprocket wheels 48. The other end of the chain 52 passes around an idle sprocket wheel 54. Outstanding from the sprocket chain 52 are a series of fingers 55 spaced apart at an amount equal to the spacing of the presser bars. Each presser bar is shown as provided with an outwardly extending lug 56 adapted to engage behind one of the fingers 55. In this way the varying travel of the presser bars 90 is communicated through the lugs 56 and fingers 55 to the chain 52. This transmission will be positive and continuous, since as seen in Fig. 3, one finger may not disengage a lug until the succeeding finger has been engaged by the succeeding lug. The chain 52 therefore partakes of the varying travel of the presser bars. In turn this chain acting through the sprocket wheel 53 and shaft 50 rotates the sprocket wheels 49 and thereby 95 advances the cover feeding chains 46 in exact 100 105 harmony with the travel of the bars.

Thereby not only are the cover applying operations and the pressing of the book backs maintained in exact synchronism with the 110 travel of the books, but also the feed of the covers to the platens or bars and the positioning of the covers during the applying action are maintained in the same synchronism.

The step of cover breaking may be performed in cooperation with the back pressing action of the bars 29 and simultaneously therewith. The cover breaking may be performed in different ways, for example by delivering to each traveling book a momentary 115 120 squeezing or shaping blow by straight jaws or plates operating from the opposite sides, on the principles disclosed in my said prior Patent 1,248,252. On the other hand the straight breaker jaws can be brought forcibly 125 130 to the sides of the book above the presser bars and held there while traveling forwardly during a substantial extent of travel of the book. This may be done either by providing a separate pair of cover breaking jaws 130

in association with each one of the presser bars or platens 29 and causing each of them by cams, rollers or the like to be moved against the book and held pressed there during the synchronous travel of the book, the bar and the jaws. In lieu of using a series of pairs of jaws such breaking action may be by a single pair of jaws moved inwardly against the book above the presser bar, moved forwardly with the presser bar while maintaining shaping pressure on the book, moved away from the book, and returned for repetition of action on the succeeding book. In lieu of these modes of cover breaking, by means of straight jaws, the action may be a progressive shaping action by rotary means operating above each presser platen. In any of these cases the action of the cover breaking means may be synchronized exactly with the periodically variable travel of the book, on the principles already herein explained.

Of these modes of cover breaking, the one shown in prior Patent 1,248,252 is herein disclosed. There is no substantial disadvantage due to lack of coordination between the variable travel of the book and the cover breaking action due to the fact that the latter is in the nature of a momentary or sudden pressure or blow, the opposite jaws not traveling forward to any substantial extent with the book.

The cover breaking mechanism is best shown in Figs. 2, 3 and 4 and further details may be ascertained from said prior Patent 1,248,252. The two opposite breaker jaws or plates 60 are mounted upon opposite longitudinal bars 61, each of which rests upon the top side of two cranks 62, so that each of the two jaws is adapted to undergo a circular motion without departing from parallelism with the advancing travel of the book. Each of the two pairs of supporting cranks 62 is mounted upon vertical shafts 63 turning in bearings 64 and carrying bevel gears 65 at their lower ends engaged by bevel gears 66 mounted on transverse shafts 67 in such manner as to give opposite directions of circular movement to the two breaker jaws. The two transverse shafts 67 are, by a set of gears 68, interconnected with each other and with an additional pair of transverse shafts 69, one of which is provided with a bevel gear 70 engaging a similar gear 71 on the drive shaft 13. In this way the cover breaking mechanism is operated from the drive shaft in coordination with the other elements of the machine.

The described principles of coordination of operations with the periodically variable book travel are applicable to apparatus having either a clamp train or some other endless or continuous conveyor carrying a succession of books, such for example as a conveyor consisting of independent but opposed book clamping elements, traveling in parallel

paths while conveying the book, and thereafter in different paths. Also the principles may be employed for other operations upon continuously conveyed books than those stated, such as the operations of rounding, backlining, backing, or casing in.

There has thus been described a bookbinding or covering machine or apparatus constructed and operating on the principles of the present invention and attaining the recited objects and advantages. Since many matters of combination, arrangement, operation, mechanism and detail may be variously modified without departing from the principles of the invention it is not intended to limit the latter to such matters except to the extent set forth in the appended claims.

What is claimed is:

1. In a book binding or covering machine, a traveling conveyor for advancing a succession of books to be operated upon, a means for operating upon the successive books during travel, a common drive member or shaft, connections for advancing the conveyor comprising a first sprocket wheel and rigid link follower between the drive member and conveyor, and connections for actuating the operating means comprising, between the drive member and operating means, a second sprocket wheel, and a second rigid link follower engaged thereby in an actuating relationship timed correspondingly to that of the first sprocket and follower, whereby periodic variations of conveyor travel speed due to the action of the first sprocket wheel are substantially neutralized by synchronous periodic variations in the action of the operating means.

2. In a book binding or covering machine, a traveling conveyor composed of an endless train of circulating articulated clamps for holding and advancing a succession of books to be operated upon, a means for operating up the successive books during travel, a common drive member or shaft, connections for advancing the conveyor comprising a first sprocket wheel and rigid link follower between the drive member and conveyor, and connections for actuating the operating means comprising a second sprocket wheel and rigid link follower, said first and second sprocket wheels having corresponding numbers of engaging points and being engaged with their respective followers in corresponding timed relationship, whereby the conveyor travel and the action of the operating means are synchronized.

3. In a book binding or covering machine, a traveling conveyor composed of an endless train of circulating articulated clamps for holding and advancing a succession of books to be operated upon, a means for operating upon the successive books during travel, composed of an endless train of circulating operating devices, a common drive

member or shaft, connections from the drive member for advancing the conveyor comprising a sprocket wheel directly engaging the articulated conveyor clamp, and connections from the drive member for actuating the operating means comprising a second sprocket wheel directly engaging the train of operating devices, said first and second sprocket wheels being engaged in corresponding timed relationship with the parts driven by them respectively, whereby periodic variations of conveyor travel speed due to the action of the first sprocket wheel are substantially neutralized by synchronous periodic variations in the action of the operating means.

4. A machine as in claim 1 and wherein the two sprocket wheels have the same effective diameters and numbers of engaging points, thereby to cause identical variations of travel and action in the conveyor and operating means.

5. A machine as in claim 3 and wherein the sprocket wheels have equivalent diameters and numbers of engaging points and the latter are timed for simultaneous engagement with and disengagement from the trains of clamps and devices respectively.

In testimony whereof, I have affixed my signature hereto.

ALFRED BREDENBERG.
